UNITED STATES PATENT OFFICE.

ALDEN L. PUTNAM, OF DETROIT, MICHIGAN, ASSIGNOR TO DETROIT PRESSED STEEL COMPANY, OF DETROIT, MICHIGAN, A CORPORATION OF MICHIGAN.

METHOD OF FORMING ARTICLES FROM PRESSED METAL.

1,202,892.

Specification of Letters Patent.

Patented Oct. 31, 1916.

Application filed February 23, 1916. Serial No. 79,809.

To all whom it may concern:

Be it known that I, ALDEN L. PUTNAM, a citizen of the United States of America, residing at Detroit, in the county of Wayne 5 and State of Michigan, have invented certain new and useful Improvements in Methods of Forming Articles from Pressed Metal, of which the following is a specification, reference being had therein to the accompanying drawings.

The invention relates to the manufacture of articles from pressed metal, and it is the object of the invention to produce structures which cannot be formed from uniform gage 15 sheet-metal blanks. For instance, in the formation of many articles of cast-metal it is advantageous to rib or emboss the structure in various places to increase the strength thereof, and while the general form 20 of the structure can be fashioned from sheet-metal it is practically impossible to produce such ribs and bosses. I have therefore devised a method of producing a ribbed or embossed structure from pressed wrought 25 metal as hereinafter set forth.

In the drawings I have shown my improved process as applied to the manufacture of pressed sheet-metal engine piston, in which—

30 Figure 1 is a plan view of the blank forming the first step in the process; Fig. 2 is a cross-section on line 2—2 Fig. 1; Fig. 3 is a vertical central section through the press- 35 ing and forming dies showing the blank be- fore the pressing operation; Fig. 4 is a lon- 40 gitudinal section through the piston after the completion of the pressing operation; Fig. 5 is a similar view in a plane at right angles to Fig. 4; and Fig 6 is a bottom plan view.

Broadly described, my improved process 45 comprises the formation of a ribbed or embossed but otherwise comparatively flat blank, by drop forging or equivalent means, and in then pressing said blank to re-fashion the same into its final form. With the specific structure shown, A is a circular blank formed by drop forging and fashioned to have a central portion B with radial ribs C 50 and a central boss D. Surrounding the portion B is an annular portion E of greater thickness and at the point of change of gage of the metal is a curved fillet F. Surround- 55 ing the annular portion E is another annular portion G, and at two diametrically op-

posite points there are formed on this portion G the hollow bosses H. All of the portions of the blank as above described can be readily fashioned by drop forging, as the draft is all in one direction.

To impart a cupped form to the blank it is pressed in suitable dies, such as the ring die I and the plunger die J. The latter is formed of a central portion K and a series of separable segments L surrounding 60 the same, said segments upon diametrically opposite sides being cut-away at M to form a pocket for receiving the bosses H. The central portion of the plunger K is enlarged 65 above the segments L to form a shoulder N 70 for bearing thereagainst, and this shoulder is also cut-away at O to form a complementary portion of the recesses for receiving the bosses H.

In performing the pressing operation the 75 blank is centered by the engagement of the central embossed portion D with a recess P in the end of the plunger, and as the metal is forced down in the annular die I the outer peripheral portion G is bent up- 80 ward or cupped. This cupping operation may be repeated with a series of annular dies of different diameter until the portions E and G of the blank become cylindrical 85 in form, the portion E being of greater thickness than the portion G and occupying an annular recess Q in the segmental dies L. The bosses H are also forced into the recesses M and O so as to be in axial alignment with each other. The hollow pis- 90 ton thus formed has a ribbed head portion formed of the portion B, a thick cylindrical wall adjacent thereto formed of the portion E and a thinner wall formed of the portion G. Both the portions E and G may 95 be readily fashioned into the cylindrical form with the exception of that part of the portion G from which the boss H projects, but the rigidity imparted to the structure at this point would render the bending of 100 the same difficult. I therefore form in the original blank a segmental portion R upon the opposite side of the blank from the bosses H, and through the cupping opera- 105 tion this segment is drawn into and becomes a portion of the cylindrical wall without changing its curve.

If the cupping operation were performed by a solid plunger instead of a sectional one, it would be impossible to remove said 110

plunger from the cup because of the interlocking with the bosses H. With the sectional plunger, however, the several sections L may be separately removed without difficulty.

The pressed metal structure formed as described may be completed by the usual machining operation of boring the bosses H and cutting annular grooves S in the heavy 10 wall E for receiving the piston rings. The boss D also provides metal for a center for turning the piston and may be removed subsequent to the machining operation.

While I have described my method as 15 applied to the production of one specific structure it is obvious that it is equally applicable to various forms in which it is desirable to provide a pressed sheet-metal structure with ribs or bosses which cannot 20 be formed by pressing.

What I claim as my invention is:

1. The method of forming pressed metal articles, comprising the forming of a substantially circular comparatively thin gage 25 blank having projecting portions of greater thickness distributed with respect to predetermined positions in the completed article, and drawing the blank to re-fashion the thinner portions thereof and to re-arrange 30 the thicker portions.

2. The method of forming pressed metal articles, comprising the forming of a substantially circular blank with a re-fashionable thin portion and a plurality of projecting thickened portions fashioned to final form, and drawing the blank to re-fashion 35 said thin portion and to re-arrange the thickened portions.

3. The method of forming pressed metal 40 articles, comprising the preliminary forming of a substantially circular blank by drop forging, said blank having re-fashionable thin portions and thick portions fashioned to final form, and drawing said blank to re-fashion the same and re-arrange the thick 45 portions.

4. The method of forming pressed metal articles, comprising the forming of a comparatively thin substantially circular blank

50 with a plurality of projecting thickened portions fashioned to a final contour, and drawing the blank to re-fashion the thin portion to be complementary to the pre-fashioned thickened portions.

5. The method of forming pressed metal 55 articles, comprising the forming of a comparatively thin blank by drop forging, said blank being provided with radially-extending thickened ribs and projecting thickened embossed portions, and pressing said blank 60 to cup the same.

6. The method of forming pressed metal articles, comprising the forming of a comparatively thin blank by drop forging, said blank having an annular thickened portion 65 with thin portions on opposite sides thereof, and pressing said blank to cup the same, forming the head of the inner thin portion and a cylindrical wall of the intermediate thickened portion and outer thin portion.

7. The method of forming pistons, comprising the forming of a drop forging having a central thin portion, a surrounding annular thickened portion and an annular thin portion surrounding said thickened portion, being also provided with projecting thickened embossed portions, and pressing 75 said blank to draw said annular thick and thin portions into cylindrical form and to arrange said embossed portions transversely 80 in alinement with each other.

8. The method of forming pistons comprising the forming of a substantially flat blank having a comparatively thin center portion reinforced by radial ribs, and the drawing of the outer portion of the blank 85 to form the cylindrical wall of the piston.

9. The method of forming pistons, comprising the forming of a drop forging having projecting thickened embossed portions, and pressing said blank to draw 90 its outer portion into cylindrical form and to arrange said embossed portions transversely in alinement with each other.

In testimony whereof I affix my signature.

ALDEN L. PUTNAM.
